Primary Examiner — Jennifer Rivard(74) *Attorney, Agent, or Firm* — Varnum, Riddering, Schmidt and Howlett, LLP(57) **CLAIM**

I claim the ornamental design for the nail design label sheet, as shown and described.

DESCRIPTIONFIG. 1 is a front view of a nail design label sheet;
FIG. 2 is a side view of a nail design label sheet; and,
FIG. 3 is a top view of a nail design label sheet.
The broken lines illustrate portions of the nail design label sheet and form no part of the claimed design.**1 Claim, 2 Drawing Sheets**Fig. 1
